UNITED STATES PATENT OFFICE.

LEVIN D. VAUGHAN, OF PHILADELPHIA, PENNSYLVANIA.

VALVE.

Application filed May 4, 1921. Serial No. 466,643.

To all whom it may concern:

Be it known that LEVIN D. VAUGHAN, a citizen of the United States, residing at Philadelphia, in the county of Philadelphia and State of Pennsylvania, has invented 5 certain new and useful Improvements in Valves, of which the following is a specification.

My invention relates to valves and has for 10 its principal object the provision of means for releasing air and other pressure on a radiator system of hot water heating.

With these objects in view, and others as 15 will appear as the description proceeds, the invention comprises the various novel features of construction and arrangement of parts which will be more fully described hereinafter and set forth with particularity in the claims appended hereto.

20 In the accompanying drawings which illustrate the preferred embodiment of my invention,

Figure 1 is a vertical sectional view 25 through the valve embodying the present invention, the valve being arranged for use in a vertical pipe; and

Figure 2 is a perspective group view 30 illustrating the parts of the valve about to be assembled.

35 Like numerals of reference refer to like parts throughout the drawings.

The numeral 10 represents a valve casing comprising a rounded body portion 10', a rounded cap or head 11 provided with the 40 extending exteriorly threaded portion 12 and an integral hexagonal nut 14 beneath said head 11, whereby said head 11 may be threaded into the interiorly threaded upper part of the body portion 10' of the valve casing 10.

Said body portion 10' is rounded, substantially, centrally, as illustrated, and has the interiorly threaded outlet 15 in one side thereof and a like interiorly threaded inlet 45 16 in its base to engage a vertical pipe.

A valve seat 17 is provided at, substantially, the base of the side outlet 15, in the interior of the body portion 10' of the valve casing 10.

50 The valve stem 18, terminating in an inverted cone shaped valve proper 19, provided with the spirally extending grooves 20 therein, resulting in spiral blades 21, is adapted to seat upon said valve seat 17, the 55 spiral blades 21 thereof extending below said seat 17 and within the inlet 16. When

the valve lifts the water flowing through the spiral grooves 20 will cause the said valve to rotate, thereby preventing uneven wear of said valve.

60 The threaded portion 12 of the head 11 is counterbored as at 22 to form a shoulder 23 and a spiral spring 24 is positioned around said valve stem 18 and is adapted for compression between the said shoulder 23 and the top of the valve 19. An opening or bore 25 in the threaded portion 12 of the cap 11 provides a guideway for the travel of the valve stem 18. A screw driver slot 26 is provided in the upper end of the valve stem 70 18 so that said valve 19 may be ground upon the seat 17, if necessary.

75 A washer 28 is provided between a hexagonal lock nut 27 threaded on the exterior threaded portion 12 of the head 11 and the open end of the body portion 10' of the valve casing 10.

In operation:—The valve is assembled, 80 the inlet 16 being connected to a vertical pipe from a tank having a radiator connection (not shown), or other suitable source of supply, and the outlet 15 to a vent pipe, or other outlet. The valve is then set for a given pressure by means of the lock nut 27. When this given pressure is had the valve 85 releases thereby releasing the air in the top of the tank, or supply means, to which said inlet 16 is connected and permits the water therein to pass thru the valve 19 and out the outlet 15 by reason of the lifting of said 90 valve from the seat 17 when the pressure is relaxed. When the pressure again becomes normal said valve will reseat itself; said valve thereby acting as a releasing valve. Said valve may also be used for other 95 advantageous ends.

From the foregoing description, taken in connection with the accompanying drawings, the advantages of construction and of the methods of operation will be readily apparent to those skilled in the art to which the invention appertains.

What I claim as new and desire to secure by Letters Patent is:—

1. A pressure relief valve structure comprising, a casing provided at one end with a tubular inlet and having a valve seat at the inner end of said tubular inlet, said valve seat being conical, said casing having an elongated sleeve at its end opposite to the 105 tubular inlet and also having an outlet upon one side thereof, a conical valve mounted 110

upon the conical valve seat and provided upon its outer end with twisted flanges extending outwardly from the conical valve and positioned within the tubular inlet, a 5 relatively long stem rigidly secured to the valve and projecting into the elongated sleeve, a single integral element embodying a cap and a relatively long extension, said extension being exteriorly threaded to have 10 screw threaded engagement within the elongated sleeve, said relatively long extension having a main longitudinal opening of substantial length slidably receiving the end portion of the valve stem, said extension 15 having a counterbore formed in its inner end surrounding the main longitudinal opening, and a compressible coil spring surrounding the valve stem with one end engaging the valve and the other end seated within the 20 counterbore, said single integral element being adjustable to regulate the tension of said spring, and means to lock said element in adjustment in a selected position.

2. A pressure relief valve structure comprising, a casing provided at one end with 25 a tubular inlet and having a conical valve seat arranged adjacent thereto, said casing having an elongated sleeve at its end opposite to the tubular inlet and also having an 30 outlet upon one side thereof, a conical valve mounted upon the conical valve seat and

provided upon its outer end with twisted flanges extending outwardly therefrom and positioned within the tubular inlet, a relatively long stem rigidly secured to the valve 35 and projecting into the elongated sleeve and provided at its free end with a transverse slot for receiving the end of the screw driver so that the valve may be ground upon its seat, a single integral element embodying a 40 cap and a relatively long extension which is exteriorly threaded to have screw threaded engagement within the elongated sleeve, said extension having a main relatively long 45 opening extending longitudinally thereof to receive the end portion of the valve stem, said extension having a counterbore formed in its inner end surrounding the main longitudinal opening, a compressible coil spring 50 surrounding the valve stem with one end engaging the valve and the other end seated within said counterbore, said element being adapted to be turned to adjust the tension of said spring and being adapted to be bodily removed from its sleeve to afford access 55 to the slotted end of the valve stem, and a lock nut having screw threaded engagement with said extension and adapted to bind against said sleeve.

In testimony whereof I affix my signature. 60

LEVIN D. VAUGHAN.
